UNITED STATES PATENT OFFICE.

NATHAN FRIEDMAN, OF CHICAGO, ILLINOIS, ASSIGNEE OF ONE-HALF TO F. H. GUNTHER, OF CHICAGO, ILLINOIS.

RUG-CLEANING MACHINE.

1,122,097.

Specification of Letters Patent.

Patented Dec. 22, 1914.

Application filed July 21, 1914. Serial No. 652,183.

To all whom it may concern:

Be it known that I, NATHAN FRIEDMAN, a citizen of the United States, residing at Chicago, in the county of Cook and State of Illinois, have invented certain new and useful Improvements in Rug-Cleaning Machines, of which the following is a specification.

This invention relates to machines for cleaning rugs, carpets and similar articles, and its object is to provide a simple and highly efficient machine of this kind embodying certain novel features of construction and operation to be hereinafter described and claimed.

15 In order that the invention may be better understood, reference is had to the accompanying drawings, in which—

Figure 1 is a side elevation of the machine; Fig. 2 is a plan view thereof, partly broken away; Fig. 3 is a longitudinal section on the line 3—3 of Fig. 2; Fig. 4 is an end view of the machine; Fig. 5 is a perspective view of a rug clamping device, and Fig. 6 is a sectional view showing the means for attaching 25 said device to the rug-carrying chain.

Referring specifically to the drawings, the supporting frame of the machine comprises spaced side walls 10 mounted on a suitable base 11, and a top 12 which is inclined and 30 has a hinged section 13. At the highest end of the frame is mounted a vertical partition 14 forming a backing plate. Along the top 35 of the frame, parallel thereto, runs a rug carrier in the form of two laterally spaced endless chains 15. At the highest end of the frame, on both sides thereof, are top and bottom sprocket wheels 16 and 17, respectively, over which the chains are trained, these sprocket wheels being so positioned relative to the partition 14, that the rug carried by the chains, when the latter are in motion, is caused to travel upward in front of the partition. At the lower end of the frame, on each side thereof, are sprocket wheels 18 45 over which the chains also pass. The lower run of the chains is horizontal, this portion of the chains being located a short distance above the plane of the base 11. The upper run of the chains is inclined to conform to the inclination of the top of the frame. The sprocket wheels 18 are fast on a transverse shaft 19 which is connected by means of a belt 20, or otherwise, to a suitable source of power. On the shaft 19 is also fast a wide pulley 21 over which pass the drive belts 22

and 23 of the beater, and the brushing and scouring devices to be presently described, the belt 22 being crossed.

The beater comprises a transverse shaft 24 journaled in the side walls 10 and carrying a drum 25 armed with flexible beater arms 26. On the shaft 24 is a pulley 27 over which the drive belt 22 passes. The beater is located above the top of the base 11 and the lower run of the rug carrier chains 15, 65 so that the rug which is being dragged across said base is acted on the beater arms 26.

In the base 11, directly beneath the beater is a dust outlet opening which is covered by a screen 28 and communicates with a dust 70 collecting casing or receptacle 29 connected to a suitable suction apparatus 30.

In front of the partition 14 are located vertically spaced, rotary, cylindrical brushes 31 and 32, positioned respectively near the bottom and the top of the partition. The shafts 33 and 34 of the respective brushes pass through horizontal slots 35 in the side walls 10, and on the outside of said walls are bearings for said shafts, said bearings being plates 36 80 which are movable horizontally to the extent of the length of the slots 35. Springs 37 anchored to the side walls and connected to the plates 36 draw the same in the direction of the partition, and thus the brushes are yieldingly pressed against the rug to allow thicker portions to pass.

On the brush shaft 33 is a pulley 38 over which the drive belt 23 passes, and said brush shaft is connected to the brush shaft 90 34 by a chain-and-sprocket or other suitable gearing 39, both brushes being thus driven in the same direction.

Between the brushes 31 and 32, a short distance above the former, are located two 95 vertically spaced horizontal pipes 40 and 41, respectively, having spray perforations. The pipe 41 is designed to spray liquid soap on the brush 31, and the pipe 40 discharges water on the rug to remove the soap. Above 100 the pipes 40 and 41 is mounted a squeegee 42, the same having supporting arms 43 which are pivoted on the pipe 40. A spring 44 coiled around the pipe 40 and pressing against the back of the squeegee holds the 105 same pressed against the rug.

The following device is provided for attaching the rug to the carrier chains 15: A clamping member composed of two longitudinal bars 45 connected by a hinge joint 46 110

at one of their longitudinal edges, is applied to one end of the rug, said end being placed between the bars and the latter being swung closed to grip the rug. In order to obtain a better hold, one of the bars has protuberances 47 which are opposite perforations 48 in the other bar. When the bars are swung closed, portions of the rug are pushed into the perforations by the protuberances, and 10 the rug is thus securely clamped. At each of the ends of one of the plates, on the inner face thereof, is an outstanding headed pin or stud 49 which passes through a perforation in the other plate when the two 15 plates are closed together. A hook 50 carried by the last-mentioned plate is swung over the pin, behind the head thereof, which prevents withdrawal of said pin, and the plates are thus locked in clamping position. To release the rug, the hook is swung off the pin, after which the plates may be 20 swung open, which leaves the rug free.

The rug clamping device is designed to be connected to the chains 15. At the ends 25 of the device are outstanding hooks 51, and certain links of the chain have an eye portion 52 through which the hooks are adapted to be passed. In the bill and the shank of the hook are alined apertures through which 30 is passed a bolt 53 secured by a nut 54 after the hook is inserted through the part 52, whereby the hook is prevented from slipping out. The clamping device extends transversely between the two chains, and the 35 rug is thus positioned between the chains. The rug, which is shown at 55, being connected to the chains 15, and the machine being started, the operation is as follows: The chain 15 travels in a direction to carry 40 the rug from the beaters 26 to the brushes 31 and 32, and the rug is connected to the chains so that it will be acted on by the beaters first. The rug is dragged along the top of the base 11 by the chains, the dust 45 knocked out by the beaters being taken up by the dust receptacle 29. Upon reaching the partition 14, the rug travels upward between the same and the brushes 31 and 32. The brush 31 receives a supply of liquid 50 soap from the pipe 41 and applies the same to the rug. The pipe 40 sprays water on the rug. The rug next reaches the squeegee 42, and finally passes the brush 32, which latter is dry and serves to brush the surface of the rug clean of any soap or water which may have remained thereon. The rug, after it clears the brush 32, travels 55 down the inclined top of the supporting frame, at the end of which latter is located a roller 56 on which the cleaned rug is adapted to be fastened and wound. The roller is removably mounted between standards 57, the same having slots 58 in which

the journals of the roller seat, said slots permitting ready removal of the roller with 65 the rug wound thereon. The roller is driven from the shaft 19 by means of a belt 59 passing over pulleys on said shaft and on one of the journals of the roller. Beneath the brush 31 is located a portable receptacle 70 60 to catch the soap and water as it runs off the rug.

The vertical position in which the rug is acted on by the brushes is advantageous as it allows a maximum surface to be brushed 75 and scoured, and also permits easy drainage. The rug is also accessible and easy to observe.

By having the top 12 and its hinged section 13 inclined, the dimensions of the machine are considerably reduced, and only three sets of guide sprocket wheels for the rug-carrying chain are required.

I claim:

1. A cleaning device of the kind stated 85 comprising a supporting frame, a vertical transverse partition near one end of the frame, sprocket wheels at the opposite end of the frame on the sides thereof and at the bottom, vertically spaced sprocket wheels at 90 the first-mentioned end of the frame at the sides thereof, said last-mentioned sprocket wheels being located respectively adjacent to the top and bottom of the partition, endless chains connecting the sprocket 95 wheels at the respective sides of the frame, gripping bars carried by the chains and extending transversely therebetween for holding the article to be cleaned, cleaning devices located in front of the aforesaid transverse partition, and a receiving roller mounted at the second-mentioned end of the frame above the sprocket wheels thevreat.

2. A cleaning device of the kind stated comprising a supporting frame, a vertical 105 transverse partition near one end of the frame, sprocket wheels at the opposite end of the frame on the sides thereof and at the bottom, vertically spaced sprocket wheels at the first-mentioned end of the frame at the 110 sides thereof, said last-mentioned sprocket wheels being located respectively adjacent to the top and bottom of the partition, endless chains connecting the sprocket wheels at the respective sides of the frame, gripping bars carried by the chains and extending transversely therebetween for holding the article to be cleaned, and cleaning devices located in front of the aforesaid transverse partition.

In testimony whereof I affix my signature in presence of two witnesses.

NATHAN FRIEDMAN.
